在這裏，我們要指出，我們在討論的問題上，並沒有與列寧的觀點相矛盾。列寧在《列寧全集》第12卷第12頁上說：「在蘇聯，我們已經有了許多的民族問題，這些問題在蘇聯的社會主義發展史上，是前所未有的。」

UNITED STATES PATENT OFFICE

2.387.400

STOKER GAS BACK

Fred G. Julyan, Euclid, Ohio, assignor to
Pocahontas Fuel Company Incorporated, New
York, N. Y., a corporation of Virginia

Application May 19, 1944, Serial No. 536,393

2 Claims. (Cl. 110—44)

This invention relates to coal stokers and particularly to such stokers of the underfeed type.

The object of the invention is to provide a system for feeding, heating and burning of the coal and disposing of the ashes, which will automatically intercept and draw off any volatiles developing in the coal feed adjacent the burner.

Further objects of the invention, particularly in the special construction of portions of the mechanism to draw off the volatiles into the space under the grate will appear from the following description taken in connection with the accompanying drawing, in which

Fig. 1 is a vertical sectional view of typical stoker mechanism embodying the invention, and 15

Fig. 2 is a horizontal sectional view taken on line 2-2 of Fig. 1.

In the stoker shown the coal tube 5 is continued to the left beyond the retort R as the ash tube 5a and the coal worm 6 in cooperation with the reverse flights 7 feed the coal up into the retort R and the worm shaft carries the disk 8 separating the coal and ash portions of the tube, the ash flights 9 receiving the ash from above and conveying it outward toward the left preferably to an ash seal substantially secure against the entrance of air.

The retort R has a lower base portion in horizontal separated sections carrying the upper radially formed tuyère blocks with tuyère openings 13 receiving the air supply from the air chamber 12 within the lower sections of the retort.

An ash table 14 is rotatably mounted on the retort and carries a grate 15, the construction being similar to that shown generally in the Julian and Schweickart Patent No. 2,321,389 of June 8, 1943. A dead ring 16, 17 is supported by its bracket arm 21 from the lugs 22 of the retort base and is recessed at 23 to fit the dead plate D forming the separation between the combustion chamber F and the space below the dead plate D. Rotation of the ash table 14 carries the ashes around to the discharge 18 passing the ashes down through the opening 19 in the ash tube ring 20.

The ashes accumulating in the dead ring 16, 17 fill the lower portion thereof and act as a substantial seal against the entrance of air from the space below the dead plate D into the area under the grate so that there is comparatively little air leakage, and the combustion chamber due to the chimney draft is at a lower pressure.

The coal passing up into the retort is heated so that the coal being fed tends to have some of its volatiles vaporized in a manner causing them to gas back along the coal feed. In the stoker of 5

this invention a by-pass is provided through the vertical portion 17 of the dead ring 16, 17 by means of an inclined orifice 31 and a U-shaped hood or cover 25 extending downward and outward and terminating in the inclined lip 26 having a vertical edge and sides 27 fitting within the gas back tube 28 with the base portion 29 fitting the top of the coal tube 5. The bore 32 of the gas back tube 28 is centered over the by-pass orifice 30 of the coal tube 5 to provide a free passage for coal gases through the orifice 30 and bore 32, hood 25 and outlet 31 into the space underneath the grate 15. A downward extending ledge 35 from the dead ring 16, 17 closes the space between the dead ring and the adjacent portion of the gas back tube.

In this way a draft of air and gas is carried up from the top of the coal tube just at the periphery of the dead ring and close to the area of volatilization of the coal vapors, there also being a slight indraft of air from the outer portion of the coal tube so that leakage of the coal gas is effectively prevented. By virtue of this arrangement, the coal tube 5 is always under a minus pressure and gases are being drawn through the dead ring 17, grates 15 and the fuel bed in the combustion chamber E.

The outlet 31 through the dead ring and the accumulating hood for this outlet are preferably formed with the dead ring during casting but may involve a separate construction. The gas back tube 28 and its base 29 form a separate unit readily inserted in place and removable without disturbing any of the other parts. It is only necessary to slide this gas back tube lengthwise on the coal tube 5 to open up the by-pass for inspection. The construction tends to be self-cleaning. Any ashes finding their way up and over into the by-pass will fall down into the coal supply and be carried on into the retort with the coal. The by-pass is of generous cross section and is kept at a temperature sufficiently high to avoid condensation of the volatiles of the coal gas so that these gases are kept from accumulating within the gas back passage by condensation.

No extra parts beyond the gas back tube itself are required and the construction is inexpensive, rugged and readily positioned and removed.

I claim:

1. In a stoker construction having a retort and a grate around the upper portion of said retort, a dead ring around said retort at a lower level and forming an ash space adapted to receive ashes at the bottom below said grate, an orifice structure carried by said dead ring and opening laterally in-

to said ash space and above the normal level of the ashes therein and below said grate, a coal tube passing beneath said dead ring and having an opening and a gas back tube extending from said opening to communicate with said orifice structure and form a passage from said coal tube to said ash space.

5 2. A stoker construction as set forth in claim 1 in which the orifice structure carried by said dead ring comprises a hood formation on the dead ring and the gas back tube is carried by the coal tube in position to be moved horizontally into cooperation with said orifice structure.

FRED G. JULYAN.
